UNITED STATES PATENT OFFICE.

ALFRED B. BREEZE, OF CINCINNATI, OHIO, ASSIGNOR TO THE CINCINNATI BALL CRANK COMPANY, OF OAKLEY, CINCINNATI, OHIO, A CORPORATION OF OHIO.

STEERING REACH ROD.

Application filed September 3, 1920. Serial No. 408,024.

To all whom it may concern:

Be it known that I, ALFRED B. BREEZE, a citizen of the United States, and residing at Cincinnati, in the county of Hamilton and

5 State of Ohio, have invented a new and useful Improvement in Steering Reach Rods, of which the following specification is a full disclosure.

My invention relates to ball joints and 10 casings thereof, and has particular relation to those joints embodying tubular casings having apertures in the side wall thereof from which the ball arm extends.

One feature of the invention relates to 15 the provision of a casing having additional strength at the ball arm aperture thereof where the casing is inherently weak and where the stress is greatest, all with a view toward relative lightness and strength. A 20 feature supplemental to this resides in the provision of a casing of the above character which is adapted to accommodate a relatively large joint ball.

Another feature resides in the provision 25 of an integrally formed ball joint casing embodying any or all of the above features, which provides a relatively light and strong double joint casing, thus obviating the necessity of a number of parts being assembled 30 to form the double joint casing.

Other features reside in the provision of a relatively compact, light, and durable joint, which is easy to assemble and which does not require exact machining of the 35 parts to effect a proper seating of the joint ball and its engaged bearing members.

Another feature relates to the provision 40 of novel means for maintaining the joint in assembly, this means being simple and well adapted to prevent accidental removal of the parts, thus providing a great factor of safety.

Another feature resides in the provision 45 of means for easily lubricating the joint which does not necessitate an additional aperture in the casing and which is well adapted to the means for maintaining the joint in assembly above mentioned.

The above features and certain other features hereinafter appearing are embodied in 50 the preferred form of my invention herein-after fully described and illustrated in the accompanying drawing, and are effected by

certain novel constructions, combinations, and arrangements of parts particularly 55 pointed out in the claims.

In the said drawing—

Figure 1 is a longitudinal section of a 60 double ball joint as a reach rod for automobile steering mechanism embodying the features of my invention.

Figure 2 is a view in elevation of the casing shown at the right of Fig. 1 with the clamp collar hereinafter described, mounted 65 thereon.

Figure 3 is a view in end elevation of the 70 collar proper mounted on the casing as hereinafter described.

Figure 4 is a view in end elevation of the complete joint.

Like characters of reference indicate like parts in the various views.

The casing of each joint is adapted to be formed of seamless steel tubing shaped by the usual processes, and comprises a tubular 75 formation 1 at the hub end of the reach rod having a ball arm aperture 2 in its side. The casing is thickened at the apertured portion thereof, as designated at 3, to give additional strength to the casing at the aperture thereby compensating for the loss of strength caused by the aperture. The casing is preferably thickened exteriorly so that the normal portion of the casing may be relatively small and light in weight. The casing 80 of each joint is reduced at one end, beyond the aperture 2, as designated at 4, to form an interior abutment surface 5 facing toward the aperture.

Where a double ball joint is required the 85 double ball joint casing is integrally formed, as shown in Fig. 1, the tubular formation being reduced, as shown at 4, between the apertures 2 adjacent each end to form a relatively light connecting rod portion, this 90 portion preferably being reduced both in external and internal diameter to form the interior abutment surfaces 5.

The aperture 2 of the casing is elongated 95 longitudinally of the casing and has an enlarged portion 6 at one end to permit the insertion of the joint ball 7, attached to the end of the usual crank ball arm, not shown. The remaining narrower portion 100 of the aperture is narrower than the diameter of the ball to confine the same with-

in the casing. Where the abutment surface 5 is provided to cooperate with the joint ball mounting in the casing to confine the ball longitudinally of the casing, the enlarged portion 6 of the aperture is disposed at the end of the aperture opposite the abutment surface.

Disposed within the casing on opposite sides of the joint ball longitudinally of the casing are two bearing elements 8 provided with the usual spherically concave bearing surfaces engaging the ball, and screw threaded into the open end of the casing opposite the reduced end 4 is an abutment member 9, which abutment member cooperates with the abutment surface 5 through a coiled compression spring 10 to clamp the assemblage of the ball and bearing elements together to engage the ball for universal movement at a point opposite the narrow portion of the aperture. The two joints shown in Fig. 1 show slight modification of this assemblage, the joint at the right showing washers 11 interposed between one bearing element and the abutment surface 5, and the spring 10 disposed between the other bearing element and abutment member 9 with washers 12 disposed between the spring and abutment member, whereas the joint at the left shows the spring 10 disposed between one bearing element and the abutment surface 5 and the other bearing element engaged directly by the abutment member.

The bearing element or ball seat 8 disposed on the side of the ball toward the enlarged aperture is provided on the side thereof opposite the ball with a concentric extension 13 of reduced cross sectional area disposed longitudinally of the bore of the casing, and the compression spring 10 of the joint shown at the right of Figure 1 interengages such extension and extends beyond the aperture into a full portion of the casing to limit movement of this bearing element laterally of the bore of the casing, whereby adequate means is provided to limit lateral movement of this member, and a relatively long spring is permissible without necessitating a corresponding elongation of the joint casing. The extension is preferably a reduced concentric extension whereby a spring of relatively large diameter may be used in the joint shown at the right of Fig. 1. Referring to the joint shown at the left of Fig. 1, the abutment member or tubular plug 9 is bored concentrically of the bore of the casing, as designated at 14, and interengages the reduced extension 13 of the adjacent bearing element 8 to afford adequate lateral thrust for the same, and to permit a longer screw threaded engagement of this abutment member with the casing without necessitating a corresponding elongation of the casing. The bore 14 extends through the length of the abutment

member just referred to and provides communication into the casing for the lubricating device hereinafter described, the abutment member 9 of the joint, shown at the right of Fig. 1, being bored similarly, as 70 is also designated at 14, to provide communication into the casing for the lubricating device hereinafter described. The bores of these two abutment members are identical so that they may be interchangeable, and 75 the bearing elements 8 disposed on the sides of the joint balls have reduced extensions 13 to provide for interchanging, the bore of the spring 10 of the joint at the left of Fig. 1 and the apertures of the washers 80 11 accommodating the same.

The external dimensions of the bearing elements 8 engageable with the various parts of the assemblage to limit the lateral movement of the bearing elements are relatively small to permit limited lateral floating movement of the bearing elements in the bore of the casing to insure a perfect bearing on the joint ball.

The joint ball 7 is of substantially the same diameter as the bore of the casing thereby effecting the positioning of the ball centrally of the casing, the bearing elements accommodating themselves to the ball in their lateral floating movement.

The casing is provided with diametrical apertures 15 adjacent the open end thereof and the abutment member 9 is provided with a diametrical aperture 16 adapted to register with the apertures 15 when the joint is assembled, and a pin 17 is engaged with these diametrical apertures to prevent rotation of the abutment member in the casing, the aperture 16 of the abutment member being elongated longitudinally of the axis of the abutment member to provide for the adjustment of the abutment member. The pin is retained in proper position by a collar 18 extending over the ends of the pin, this collar being a split clamp collar 110 clamped on the casing and including a clamp bolt 19 engaged in tangential apertures formed in the collar on opposite sides of the split thereof. The shank of the bolt preferably extends into a corresponding depression 20 formed on the casing to prevent the collar from working off of the casing unless the bolt is removed.

The clamp collar 18 is provided with a circumferential flange 21 which extends over the adjacent ends of the casing and abutment member 9 to prevent removal of the abutment member in the event that the pin 17 does not function or is omitted in assembling the joint.

A lubricating device is mounted upon the exterior end of the abutment member 9 and comprises an extension 22 formed on the exterior end of said abutment member and extending through the opening of the flange 130

21 and having a longitudinal bore continuing the bore of the abutment member, and a grease cup 23 screw threaded upon said extension. The bearing element 8 adjacent 5 the abutment member 9 is bored longitudinally of the axis of the casing, as designated at 24, to provide a lubricating communication therethrough to the joint balls, the other bearing elements 8 being bored similarly, as also designated at 24, to provide interchangeability. Thus is provided lubricating means which does not necessitate an additional aperture in the casing and which is well adapted to the construction of the 10 joint of my invention.

While I have herein shown and particularly described the preferred embodiment of my invention I do not wish to limit it to the precise details of construction shown, 20 as changes may readily be made without departing from the spirit of my invention, but having thus described my invention I claim as new and desire to secure by Letters Patent the following:

25 1. A ball joint including a tubular casing having an open end and a ball arm aperture in the side wall thereof and having diametrical apertures formed in the walls thereof adjacent said open end, a joint ball within the casing, means in the casing for engaging the ball for universal movement therein including an abutment member screw threaded into the one end of the bore of the casing, said abutment member having a diametrical aperture therein in registry with said diametrical apertures of the casing, a pin engaging the diametrical apertures of the casing and abutment member, and a collar engaging about the periphery 35 of said casing covering the ends of said pin to retain it in aperture engaging position, said collar having an inturned flange at one end engaging over the end of said casing and abutment member.

40 2. A ball joint including a tubular casing having an open end and a ball arm aperture in the side wall thereof and having diametrical apertures formed in the walls thereof adjacent said open end, a joint ball within the casing, means in the casing for engaging the ball for universal movement therein including an abutment member screw threaded into the one end of the bore of the casing, said abutment member having a diametrical aperture therein in registry 45 with said diametrical apertures of the casing, a pin engaging the diametrical apertures of the casing and abutment member, a split clamp collar clamped upon said casing and extending over the ends of said pin to retain it in aperture engaging position, and an internal circumferential flange 50 formed on said collar and extending over

the adjacent ends of the casing and abutment member.

65 3. A ball joint including a tubular casing having an open end and a ball arm aperture in the side wall thereof, a joint ball within the casing, means in the casing for engaging the ball for universal movement therein including an abutment member screw threaded in the open end of the bore of the casing and bored longitudinally, means for preventing accidental removal of the abutment member including a collar secured on the casing and an internal circumferential flange formed on the collar and extending over the ends of the casing and abutment member, and a lubricating device mounted at the exterior end of said abutment member 70 and communicating with the bore of the abutment member through the opening formed by said flange.

4. A ball joint including a tubular casing having an open end and a ball arm aperture in the side wall thereof, a joint ball within the casing, means in the casing for engaging the ball for universal movement therein including an abutment member screw threaded in the open end of the bore of the casing and bored longitudinally, means for preventing 80 accidental removal of the abutment member including a collar secured on the casing and an internal circumferential flange formed on the collar and extending over the ends 85 of the casing an extension formed at the exterior end of said abutment member and having a longitudinal bore of the abutment member and extending through the opening formed 90 by said flanges, and a grease cup screw threaded upon said extension.

5. A drag link consisting of a piece of tubing having a socket portion of enlarged diameter, a portion of the wall of said socket portion intermediate the ends thereof being thickened, said socket portion having a ball lever receiving slot therein, said slot having an enlarged ball entering portion and a narrower ball retaining portion, the enlarged 105 portion of said slot being formed in the thickened portion of the socket wall.

6. The method of forming a drag link, which comprises upsetting and expanding an end of a piece of tubing to form an end 110 socket of enlarged diameter, and upsetting the wall of the socket to form a circumferential reinforcing rib.

In witness whereof, I hereunto subscribe my name, as attested by the two subscribing 120 witnesses.

ALFRED B. BREEZE.
